Attns.

UNITED STATES PATENT OFFICE.

JOSEPH O. HOWARD, OF EVANSTON, ILLINOIS.

HOLDER.

Application filed June 1, 1926. Serial No. 112,778.

My invention relates to holders for flags, pennants, banners, and the like, and though it can be applied to different kinds of supports, it is designed particularly for attachment to the bumper bars or brackets of automobiles. The object of the invention is to provide a simple device by means of which the staffs for flags, pennants, or other devices may be quickly and securely fastened to a bumper bar or bracket and which is adjustable for application to bars of different dimensions. A further object is to make the holders so simple that they can be applied by any one without the use of any tools.

On the accompanying drawing:—

Figure 1 is a front elevational view of a section of a bumper bar showing the holder applied thereto;

20 Figure 2 is a side elevational view of the holder with the bumper bar in section; and

Figure 3 is a plan view of the parts shown in Figures 1 and 2.

The holder shown comprises a spring bow frame or strap A, and a tie link or retainer member B. The bow frame shown is formed from a single piece of spring wire.

The wire is first given a gradual bend 5 midway between its ends to bring the halves

30 into practically parallelism. Above the bend the halves or legs are each given one or more turns or convolutions 6, and the upper leg sections 7 in the finished frame being at an angle with the lower sections 8.

35 The bend 5 forms a loop, eye, or pocket for receiving the staff S of a flag, pennant, banner or the like, while the turns or convolutions 6 form abutment projections for abutting against a support, such as the bar

40 C of an automobile bumper.

The tie link or retainer member shown is a sheet metal plate having at one end the hole 9 for receiving the staff of a flag, or the like, and at its other end and on opposite 45 sides having the diagonally extending slots 10 and 11 for receiving the upper ends 7 of the bow frame.

To apply a flag, or the like, to a holder its staff is inserted through the hole 9 of the 50 tie plate B and through the bend 5 of the bow frame. The staff is then applied against one side of the support, such as the bumper bar C, with the lower leg sections 8 of the bow frame below the support and the 55 tie plate above the support. The position will then be that shown in Figure 2, with the

upper leg sections 7 still disconnected from the tie plate, as indicated by the dotted lines. These upper leg sections are now swung inwardly and deflected slightly apart 60 so that they may enter the diagonal slots 10 and 11, so that upon release of these leg sections they will then be held in the slots behind the plate sections 12 and 13 which form retaining hooks. The tie plate can then be 65 pushed down against the top of the support. Engagement of the bow frame upper leg sections with the tie plate will bring the turns or convolutions 6 into abutting engagement with the supporting bar. Bringing the 70 tie plate down against the top of the support will further flex the bow frame, and in tending to recover its normal shape the frame will exert pressure through its loops 6 against one side of the support, and pull 75 on the staff to clamp it against the opposite side of the support, and the staff will thus be rigidly held in position. To lock the staff against longitudinal displacement teeth 14 are cut in the outer side of the hole 9 of the tie plate, these teeth sinking into the staff and securely holding it against slipping.

When the flag is to be removed the leg sections 7 of the bow frame may be swung 80 further inwardly to be released from the slots 10 and 11, or the tie plate may be raised beyond the ends of the leg sections and thus released therefrom. The leg sections 7 are made of sufficient length so that supporting 85 bars of different widths may be accommodated. Abutment of the leg sections 8 against the lower edge of the supporting bar and abutment of the tie plate against the top of the supporting bar will rigidly lock 90 the holder against tilting laterally.

My improved holder is very efficient and can be readily and inexpensively manufactured. Changes and modifications are possible which will still come within the scope 100 of the invention and I do not, therefore, desire to be limited to precisely what I have shown.

I claim as follows:—

1. In a holder of the class described, the 105 combination of a spring frame having a staff receiving passageway at its lower end and abutments intermediate its ends, and a tie plate having a staff receiving opening and having notches for detachably receiving the 110 upper end of said spring frame.

2. In a holder of the class described, the

combination of a spring frame formed of wire, said frame having a staff receiving passageway at its lower end and abutment projections intermediate its ends, and a tie member having a staff receiving opening at one end and means at its other end for detachably receiving the upper end of said frame.

3. In a holder of the class described, the combination of a spring frame formed of wire, said frame at its lower end having a staff receiving passageway, convolutions in said frame intermediate its ends forming abutment projections, and a tie member having a staff receiving passageway and having notches for receiving the upper end of said spring frame.

4. In a holder of the class described, a spring frame of wire and of substantially U-shape, the bend of said frame serving to receive a staff, abutment convolutions formed in the limbs of said frame near the bend thereof, and a tie plate having a staff receiving opening at one end and side notches at its other end for receiving the upper ends of the frame limbs.

5. In combination, a support, a staff engaging against one side of said support, a spring frame of substantially U-shape and formed of wire, the bend of said frame receiving said staff below said support, abutments on said frame a distance above its bend for engaging against the opposite side of said support, and a tie member above the support having an opening for receiving the staff and having retaining means for receiving the upper ends of said frame after flexure thereof and to retain said frame in flexed condi-

tion to exert pressure against said support and pull on said staff whereby to securely hold said staff to the support.

6. In combination, a support, a staff engaging against one side of said support, and a holder structure, said holder structure comprising a spring frame and a tie member, said spring frame having an opening at its lower end for receiving the staff below the support, an abutment extension on said frame intermediate its ends for abutting against the opposite side of said support, said tie member being above the support and having an opening for receiving said staff, said tie member having notches for receiving the upper end of said frame and for retaining said frame in flexed condition, said flexure exerting pull on said staff to hold it securely clamped against said support.

7. In combination, a support, a staff against one side of said support, a spring wire frame having a loop at its lower end for receiving the staff below said support and having a deflection intermediate its ends for abutting against the opposite side of said support, and a tie plate having an opening for receiving the staff above said support and having detent notches for receiving the upper end of said frame to hold said frame in flexed condition for exerting pressure against said support and pull on the staff to clamp it against the opposite side of the support.

In witness whereof, I hereunto subscribe my name this 27th day of May, 1926.

JOSEPH O. HOWARD.
